UNITED STATES PATENT OFFICE

CHARLES I. LONGENECKER, OF MILWAUKEE, WISCONSIN, ASSIGNOR TO CHAIN BELT COMPANY, OF MILWAUKEE, WISCONSIN, A CORPORATION OF WISCONSIN

PORTABLE PUMP

Application filed December 7, 1929. Serial No. 412,552.

This invention relates to portable pumps and has for one of its objects to provide an apparatus of this character which will be simple in construction, comparatively inexpensive to manufacture and more efficient in use than those which have been heretofore proposed.

The invention relates more particularly to pumps of the diaphragm type wherein the pump casing is separable to facilitate the replacement of the diaphragms when they become worn and it is a further object of the invention to provide a readily portable pumping unit of this type in which the replacement of said diaphragms is further facilitated.

With the above and other objects in view which will appear as the description proceeds the invention consists in the novel details of construction and combinations and arrangements of parts more fully herein-after described and particularly pointed out in the appended claims.

Referring to the accompanying drawings forming a part of this specification in which like reference characters designate like parts in all of the views:

Figure 1 is a side elevational view of a portable pumping unit constructed in accordance with the present invention, the parts being shown in the positions they assume when a diaphragm is to be changed;

Figure 2 is a front elevational view of the unit with the parts shown in their normal or operating positions;

Figure 3 is a detail perspective view of the supporting frame for the pump unit;

Figure 4 is a top plan view of the frame shown in Figure 3;

Figure 5 is a side elevational view of the parts shown in Figure 4;

Figure 6 is a detail perspective view of the supporting axle and the brackets therefor, together with the ground-engaging member of the frame; and

Figure 7 is an enlarged fragmentary, sectional elevational view showing the method of attachment of the ground-engaging member to the axle, and of the axle supporting bracket to the frame member.

In the said drawings the numeral 10 indicates generally a supporting frame for the pump unit which, as will be clear from Figs. 3, 4 and 5, comprises a pair of parallel spaced Z-bars 11 which are connected together by a centrally located transverse Z-bar 12 which may be welded or otherwise suitably secured to the longitudinal members 11. Adjacent one end of each of the longitudinal members there is secured an angle bracket 13, through the downwardly dependent leg 14 of which a shaft or axle 15 extends. The brackets 13 are preferably stamped from sheet metal of suitable thickness and may be welded to the axle 15 at the points of intersection, as indicated at 16. The projecting ends of the axle 15 carry ground-engaging wheels 17 which serve to support the unit while permitting it to be readily transported from place to place as will be readily understood.

Rotatably mounted upon the axle 15 intermediate the brackets 13 is a sleeve 20 which is held against longitudinal movement upon the axle by any suitable means, such for example, as the cotter pins 21 shown in Figs. 6 and 7. Rigidly secured to the said sleeve 20 as by welding is a forwardly extending ground-engaging member 22, the extreme end 23 of which is preferably bent downwardly and has secured to it an angle member 24 which serves to reinforce the member 22, and provides a relatively broad foot therefor.

Mounted upon the forwardly extending ground-engaging member 22 is a lower section 25 of the casing of a diaphragm pump of well known construction. This casing section usually constitutes the inlet chamber and is provided with an intake port 26 as shown in Figs. 1 and 2.

The upper section 27 of the pump casing which, as is well known in pumps of this type, is separable from the lower section 25, and carries the diaphragm 28, is mounted upon the frame 10, as is also the actuating means for the pump. The actuating means may comprise a reciprocating connecting rod 29, the upper end of which is carried by crank 30 of the shaft 31, which shaft carries

at one end a gear wheel 32 meshing with a pinion 33 which is likewise mounted upon the frame 10 as will be clear from Fig. 1. The casing sections 27 and 25 are normally held together by means of bolts 36 and the nuts thereon which provide a readily detachable connection between the separable sections.

The parts are so designed, constructed and assembled that in the normal or operating position of the unit the center of gravity of the entire assembly lies to the left of the supporting axle 15, as viewed in Fig. 1 so that the device will be stable under operating conditions. In this condition it may be readily transported from place to place upon the wheels 17 by simply lifting the said end to raise the ground-engaging foot 24 off the ground as will be readily understood.

Should the diaphragm 28 become worn or otherwise defective, necessitating replacement thereof, the nuts on the bolts 36 are removed thereby permitting the separation of the members 25 and 27 which is accomplished by raising the forward end of the frame 10 through the medium of the handle 38, which tilts the upper portion of the pump, the motor 35 and the frame 10 upon the axis of the axle 15. The forwardly extending member 22 together with the lower casing member 25 remain in normal horizontal position as shown in Fig. 1. During such movement the center of gravity of the portion of the assembly constituted by the frame 10, the upper elements of the pump and the motor 35 is shifted from the left to the right of the axle 15, thereby producing a torque tending to continue the tilting of these members in a clockwise direction as viewed in Figure 1. In order to restrain this tilting movement, a suitable connection, here shown as a chain 40, is provided between the frame 10 and the ground-engaging member 22 so that when the parts reach the positions shown in Fig. 1 they will be maintained therein, thus making the replacement of the diaphragm 28 a comparatively simple matter. It will be understood that although the center of gravity of the upper tilting portion of the apparatus is shifted from the left to the right of the axle 15, the center of gravity of the entire apparatus at all times remains to the left of the axle 15 whereby the unit is prevented from tipping over entirely. In other words, the weight of the lower casing member 25 and its associated parts is sufficient to overcome the continued tendency of the upper movable parts to tilt and to maintain the entire device in the position shown in Fig. 1.

While one form of the invention has been described and illustrated it is obvious that those skilled in the art may vary the details of construction as well as the precise arrangement of parts, without departing from

the spirit of the invention and therefore it is not wished to be limited to the above disclosure except as may be required by the claims.

What is claimed is:

1. In a portable pumping unit, a supporting frame comprising a pair of pivotally connected members; and a pump carried by said frame having a separable casing, a part of said casing being carried by each of said frame members. 70

2. In a portable pumping unit, a supporting frame comprising a pair of pivotally connected members; a pump carried by said frame having a two-part separable casing, 80 each of said parts being carried by one of said frame members; and means for limiting pivotal movement of said members relative to one another.

3. In a portable pumping unit, a wheeled supporting frame including a pair of members and a wheel carrying axle constituting a pivotal connection between said members; and a pump carried by said frame having a separable casing, one part of which is carried by one frame member and the other part of which is carried by the other frame member. 85

4. In a portable pumping unit, a wheeled supporting frame including a pair of members and a wheel carrying axle constituting a pivotal connection between said members; a pump and driving means therefor mounted on said frame, said pump having a two part separable casing, one part of which is carried by one frame member; and the other part of which is carried by the other frame member; and connections between said members for limiting pivotal movement of said one member relative to the other. 95 100

5. In a portable pumping unit, a supporting frame comprising a pair of pivotally connected members; a pump carried by said frame having a separable casing, one section of which is carried by one frame member and the other section of which is carried by the other frame member, the parts being so arranged that the center of gravity of one portion of the assembly may be shifted from one side to the other of the pivotal connection through the tilting of one frame member, while the center of gravity of the entire assembly always remains upon one side of said connection; and means for limiting the tilting movement of said member relative to the other member, whereby the pump casing may be held in separated readily accessible position. 110 115 120

6. In a portable pumping unit, a frame member; an axle and supporting wheels for said member; a ground-engaging member pivotally secured to said axle; a pump section carried by said last named member; a second pump section and pump actuating 125 130

means carried by the first named frame member; and means for limiting tilting movements of said first named member and the parts carried thereby relative to said ground-engaging member.

5 In testimony whereof I affix my signature.

CHARLES I. LONGENECKER.
